D. M. WESTON.
CENTRIFUGAL MACHINE FOR DRAINING SUGAR AND OTHER SUBSTANCES.
No. 63,770.

Patented Apr. 9, 1867.

Witnessed,
August 1867
J. M. J. Howard

Inventor,
D. M. Weston

United States Patent Office.

DAVID M. WESTON, OF BOSTON, MASSACHUSETTS.

Letters Patent No. 63,770, dated April 9, 1867.

IMPROVEMENT IN CENTRIFUGAL MACHINES FOR DRAINING SUGAR AND OTHER SUBSTANCES.

The Schedule referred to in these Letters Patent and making part of the same.

TO ALL WHOM IT MAY CONCERN:

Be it known that I, DAVID M. WESTON, of Boston, county of Suffolk, and State of Massachusetts, have invented a new and useful Improvement in Centrifugal Machines for Sugar and other Material; and I do hereby declare that the following is a full, clear, and exact description of the construction and operation of the same, which will enable those skilled in the art to make and use the same, reference being had to the annexed drawings, making part of this specification, in which—

Figure 1 is an elevation of my invention.

Figure 2 is a vertical section of the same.

Figure 3 shows the pulley with the shaft and cylinder detached therefrom.

Figure 4 is a plan of the top of the cylinder within the tub.

Figure 5 is a plan of the under side of the cylinder showing the outlets in the bottom.

Figure 6 is a horizontal section of the cylinder and tub on the line A B, part of the valve being removed, so as to exhibit partially the outlets in the bottom.

a is a frame from which the invention is suspended. *b* is a box attached firmly to the frame *a*, containing the rubber bushing or spring, *c*. *c* is a rubber bushing or spring within the box *b*, in which the spindle *d* is hung. *d* is an upright spindle hung by a flange on its upper end in the rubber bushing *c*, and in which the rotary parts of the machine are hung and revolve. *e* is an upright hollow shaft encircling the spindle *d*, with a driving-pulley firmly attached to its upper end, and a revolving cylinder, *g*, attached below, supported by a screw-nut attached to the lower end of the spindle *d*. *f* is a driving-pulley attached to the upper end of the hollow shaft *e*. *g* is a revolving cylinder, with an opening in the top and perforated sides, attached to the hollow shaft *e* at its lower end, made to contain sugar or other material to be acted upon by centrifugal force. *h* is a tub in which the cylinder *g* revolves, forming a receptacle for the liquids which are separated by centrifugal force from the sugar or other material acted upon. *i i i i* are openings in the bottom of the cylinder *g*, to permit the discharge of the solid material after it is acted upon. *j* is a movable valve adjusted by a hollow neck or stem, so as to slide up and down upon the shaft *e*.

The nature of my invention consists, first, in substituting for the fixed bearings commonly used, a flexible bearing, so that the revolving cylinder, which may be made in any of the common forms, may be suspended from the top by flexible connections, so as to admit a free lateral movement while it revolves, thus overcoming the great jar and concussion which, by the uneven distribution of the weight of the materials to be acted upon, must always be created by rapid motion upon fixed bearings, thereby saving a great expenditure of power, much wear and tear of machinery, and great weight and expense of machines, and foundations to secure stability; and second, in discharging the sugar or other materials after being acted upon, from the revolving cylinder, by elevating or otherwise opening a valve in its bottom. I construct a cylinder to contain the material to be acted upon in any of the common forms, with the usual opening in the top, and with perforated sides, which I attach to the lower end of the upright hollow shaft *e*, to which, at the upper end, is affixed the pulley *f*, the whole revolving on the spindle *d*, which is suspended in the flexible bushing *c*, within the box *b*, allowing the hollow shaft *e* and cylinder *g* to revolve with a free lateral movement. In the bottom of the cylinder *g* I construct the openings *i i i i*, which may vary in form, and which are closed by the movable valve *j*, which is attached loosely to the upright shaft *e*, as shown in fig. 2. This cylinder being filled through the opening in the top, with the valve *j* resting upon and covering the openings *i i i i* in the bottom, power is applied to the pulley *f* affixed to the upright shaft *e*, and the cylinder *g*, with its contents, revolves rapidly and freely upon the spindle suspended in the rubber bushing *c*, which enables the revolving mass however unevenly its weight may be distributed, to find its own centre, upon the axis of which it revolves without jar or concussion. After the sugar or other material contained in the revolving cylinder *g* has been acted upon, and the liquids separated and discharged through the apertures in the sides by the centrifugal force thus created, the valve *j* is raised, and sliding upwards upon the shaft *e*, the contents of the cylinder are discharged through the openings in the bottom *i i i i*. It is not essential to my invention that the flexible bearings by which the rotary parts of the machine are allowed to revolve with a lateral movement should be made in the form I have above described. Other forms of bearings or joints, or flexible connections, may be made to effect this purpose, such as what is commonly called "the

universal joint," or by connecting the upright shaft with its support by means of a ball-joint or thin disk plate or other flexible connections.

I claim the construction of centrifugal machines made to separate liquids from other substances, by suspending such machines at the top by flexible connections operating substantially as above described.

I claim the construction of the openings *i i i* in the bottom of the cylinder *g*, in such machines, and the valve *j*, for the purpose and operating substantially as above described.

D. M. WESTON.
